Geo. B. Leonard

Attorney

UNITED STATES PATENT OFFICE.

ALBERT NEAL, OF KOKOMO, INDIANA.

WRENCH.

Application filed March 15, 1924. Serial No. 699,582.

To all whom it may concern:

Be it known that I, ALBERT NEAL, a citizen of the United States, residing at Kokomo, in the county of Howard and State of Indiana, have invented certain new and useful Improvements in Wrenches, of which the following is a specification.

My said invention relates to a wrench and it is an object of the same to provide a wrench of the type which grips an object more tightly the greater the resistance encountered, and which wrench shall be strong and durable.

A further object of the invention is to provide a wrench of this character which may be manufactured in an economical manner, it being made of a relatively limited number of parts.

Referring to the accompanying drawings, which are made a part hereof and on which similar reference characters indicate similar parts—

Figure 1 is a side view in elevation,

Figure 2 a similar view of the opposite side,

Figure 3 a bottom plan, and

Figure 4 a perspective of the device.

In the drawings reference character 10 indicates the handle of the wrench which in this instance consists of a single piece stamped or cut out from sheet metal and folded over at 11. The part of the handle at 11 is preferably left in somewhat expanded condition to prevent the handle from slipping out of the hand of the user. The free ends 12 are somewhat wider than the body of the handle and one of said ends has a curved slot 13 and a shorter straight slot 14, the other end having a curved slot 40 and a circular opening 16.

The opening 16 is adapted to receive a trunnion on the shank of the jaw 17 which also has a trunnion 18 spaced longitudinally of the wrench and entering the slot 15. Another jaw 19 has a pair of longitudinally spaced trunnions 20 and 21 entering slots 13 and 14.

The shanks of the jaws 17 and 19 are located on the under side of said jaws and are flat as clearly shown in Figure 4 and may be formed by die casting or in any other convenient manner. Each of the shanks has a flange 22 extending forwardly of the jaw for reenforcing its connection with the respective jaw and each of the shanks also has a flange 23 extending over

the rear end of the other shank, said flange providing with the jaw on the shank, a trough in which the shank of the other jaw is slidably located. As will be evident from consideration of Figures 1 and 2 the flanges 23 are spaced from one another to permit the necessary relative movement between the jaws.

The free ends 12 of the handle are bent so as to afford space between them for the flanges of the jaws and between said ends and the bent part 11 the side members of the handle are electrically welded together for greater strength at 24.

In the operation of my device the jaws, in wide open position as in Figures 1 and 2, are positioned at opposite sides of a nut or other object to be turned and the handle is moved down at its outer end relative to the remainder of the device. Thereupon the handle rotates relatively to the trunnion in the opening 16 of jaw 17 while the trunnion 18 moves through its arcuate slot 16. Since the shank of the jaw 19 slides on the shank of the jaw 17, the latter being in a sense the stationary body of the wrench, there must be a loose connection between the trunnion 21 and the adjacent handle portion as shown at 14 and the slot 13 also cannot be strictly arcuate with reference to the trunnion 21 but approaches nearer thereto at each end than at the middle thereby allowing full freedom of movement between the parts without needless binding.

It will be evident to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent is:

1. A wrench comprising a pair of jaws, a shank at the under side of each jaw extending forwardly of the jaw, a flange at the end of each shank opposite the jaw extending over the adjacent shank and forming with the under side of the jaw a guiding groove for the other shank, trunnions projecting laterally from the shanks said trunnions being spaced from each other transversely of the shaft and longitudinally of the wrench, and a bifurcated handle embracing the shanks each fork of the handle being piv-

totally connected to one of said trunnions, substantially as set forth.

2. A wrench comprising a pair of jaws, a shank at the under side of each jaw extending forwardly of the jaw, a flange at the end of each shank opposite the jaw extending over the adjacent shank and forming with the under side of the jaw a guiding groove for the other shank, oppositely projecting trunnions on the shanks said trunnions being spaced from each other transversely of the shaft and longitudinally of the wrench, a bifurcated handle embracing the shanks each fork of the handle being pivotally connected to one of said trunnions each fork also having an arcuate slot, and laterally projecting trunnions on the jaws extending into said arcuate slots for limiting the relative movement of the jaws, substantially as set forth.

3. A wrench comprising a pair of jaws, a shank extending forwardly from the under side of each jaw, and overlapping the other jaw, a flange at the end of the shank opposite the jaw extending laterally over the adjacent shank and forming with the under side of the jaw a guiding groove for the other shank, a pair of trunnions spaced transversely of the shaft and longitudinally of the wrench on each of said shanks, a bifurcated handle embracing the shanks one fork of the handle being loosely pivoted to

one of said trunnions, the other fork of the handle being rigidly pivoted to the other of said trunnions, each fork also having an arcuate slot spaced longitudinally of the wrench from the arcuate slot on the other fork, and laterally projecting trunnions on the jaws extending into said arcuate slots for limiting the relative movement of the jaws, substantially as set forth.

4. A wrench comprising a pair of opposed jaws having shanks extending forwardly from their under sides, in face contact with each other, each of said jaws having a forwardly extending portion forming a laterally extending flange on each shank and bearing against the underside of the opposed jaw to guide the same, each of said shanks having a flange at its end opposite the jaw extending laterally over the adjacent shank and forming with the under side of the jaw a guiding groove for the other jaw, and a bifurcated handle pivotally connected to each of said jaws for moving them relatively to each other, substantially as set forth.

In witness whereof, I have hereunto set my hand and seal at Kokomo, Indiana, this 13th day of March, A. D. nineteen hundred and twenty-four.

ALBERT NEAL. [L. S.]
